UNITED STATES PATENT OFFICE.

GEORGE PARMENTIER, OF VIENNA, AUSTRIA-HUNGARY.

BOOT AND SHOE MACHINE.

1,118,438.

Specification of Letters Patent.

Patented Nov. 24, 1914.

Application filed March 6, 1913. Serial No. 752,381.

To all whom it may concern:

Be it known that I, GEORGE PARMENTIER, a subject of the German Emperor, residing at 44 Neubaugasse, Vienna, VII, in the Empire of Austria-Hungary, have invented certain new and useful Improvements in Boot and Shoe Machines, of which the following is a specification.

The present invention relates to boot and 10 shoe machines especially to devices for lifting boots and shoes from their lasts.

The invention consists in the fact that the last-pin is formed as a spreading device, which spreads in such a manner that lifting 15 of the last is prevented with increasing certainty in proportion as forces act upon it which tend to lift it off the pin. In order to oppose a straining of the last-pin produced by binding or tilting of the last it is advantageous to support the last at the base of its 20 pin so that the last is not only secured to the pin owing to the spreading of the latter but also supported on the pin.

An embodiment of the invention is illustrated in the accompanying drawing as applied to a boot last-pulling machine in which in accordance with the invention the last is seized from below on the last hole and held upon the last-pin, whereupon, by means of 25 movable bars adapted to be driven in between the last and the boot, the boot is lifted from the fixed last.

Figure 1 shows a constructional form of such a machine in front elevation partly in section. Fig. 2 is a side elevation partly in section. Fig. 3 is a plan. Fig. 4 is a section on the line A A in Fig. 2, and Fig. 5 is a detail view.

In accordance with the embodiment of the 40 invention here illustrated the apparatus consists broadly of a last pin 1 formed of a pair of levers pivoted together after the analogy of pincers, in two or more parts, upon which the last 2 is placed and held thereon by the 45 pressure produced by the opening of the pincers. In the construction here illustrated the opening and closing of the pincers is effected by means of a pedal 3. The arrangement may be such that the pincer levers 4, 50 5 are connected one with the other by links 6, 7, the common pivot of which is fixed, and the hinge bolt 8 of the pincers is shift-

able by means of rods 9 connected with the pedal 3 so that by means of a depression of the hinge bolt produced by means of the 55 pedal the pincers 1 are closed while when the hinge bolt is shifted upward they are opened. The pincer levers 4 and 5 are thus actuated by a toggle mechanism.

The boot or shoe is pulled away from the 60 last by means of two reciprocatory bars 10, 11, mounted on a sliding member 14, adapted to be raised and lowered by a pedal 12, whereby said bars can be driven in between the last and the upper in the manner of a 65 shoe horn. In the construction illustrated the bars can be adjusted to lasts of different widths, and for that purpose they are jointed scissors-like and provided preferably with a spring 13 always tending to draw them together. The arms 10 and 11 are provided with projecting members 15 slidably engaging with adjustable guide rails 16. The interval between the guide rails 16 determines the width to which the horns open. By adjusting the guide rails 16 from or toward 70 each other the width to which the horns open will be increased or reduced. The adjustment of the guide rails may be effected for example by mounting said rails on pivoted arms 26 80 and providing a screw spindle 19 rotatable by means of a hand wheel 18 or the like. The spindle is shown provided with left and right hand threads engaging nuts 17 on the guide rails 16. This affords a turn-buckle construction.

The stroke of the horns is shown adjustable by means of an adjustable stop 21 mounted in a slot 22 in the upright 23 of the machine, and its position limits the 90 stroke of the horns.

In the construction illustrated all the members of the machine with the exception of the pedals are mounted on a cover plate 20 of the upright 23 of the machine. This 95 cover plate is secured on the upright in such a manner as to be readily detachable so that all the members are accessible merely by lifting the plate.

When the apparatus is in use in the first 100 place the last pin 1 formed as pincers is closed by means of the pedal 3 so that the last can be placed upon it. The pedal is preferably drawn back into its normal po-

sition by the action of a spring 3'; upon the release of the pedal the pincers are opened by spring action and, owing to the pressure produced thereby the last is firmly clamped 5 on its pin. Then by means of the pedal 12 the horns 10, 11 are lifted and driven between the last and the boot whereby the latter is lifted from the last and can be removed by hand. Preferably the arrangement 10 is such that the horns 10, 11 extend beyond the base of the last pin in their lowered position so that when the boot is placed upon the last-pin the horns penetrate between the last and the boot. In order to 15 avoid binding or tilting of the last and the bending strain upon its pin which would occur upon the lifting movement of the horns, a bearing (Figs. 1 and 5) is provided on the base of the last-pin, the last resting 20 upon this bearing by means of its plane face. The return of the pedal 12 to its initial position can be produced automatically by the action of springs 25 or the like which engage on the rods 24 connected with the pedal and 25 become operative when the pedal is released.

When owing to the stretching of the leather the last is drawn upward in unlasting, owing to the upward movement of the hinge bolt, the spreading device becomes operative 30 so that the greater the tendency of the last to rise the more effective is the spreading action.

It will be understood that the form of device shown in the drawings and described 35 in detail is illustrative of the invention and that changes may be made within the scope of the claims as occasion may demand.

Having now particularly described and 40 ascertained the nature of my said invention and in what manner the same is to be performed, I declare that what I claim is:—

1. A last holder for boot and shoe machines, comprising a last pin formed as a spreading device constructed and adapted 45 for engaging the walls of the last hole to fix the last in position and oppose the lifting of the same, and actuating mechanism for said pin effective upon a lifting movement on the part of the last to produce an increased spreading action of the last pin.

2. A last holder for boot and shoe machines, comprising a last pin embodying levers pivoted together after the analogy of pincers, said levers at one end constituting 55 the last pin, and mechanism associated with the other ends of said levers for spreading the pin and located in position to produce a spreading movement when the last is acted upon in such manner as to tend to lift it.

3. A last holder for boot and shoe machines, comprising a pair of levers pivoted together after the analogy of pincers, the levers at one end comprising a device for

engaging the last hole, and a toggle associated with the other ends of the levers and 65 located in such a position that an outward movement of the pin portion will cause a spreading movement thereof.

4. A last holder for boot and shoe machines, comprising a last pin constructed 70 and adapted for spreading into engagement with the walls of the last hole to fix the last in position and oppose the lifting of the same, mechanism for actuating the pin for effecting such engagements and means operable upon such lifting movement on the part 75 of the last to produce an increasing spreading action of the last pin, a shoe horn, and means for actuating the same for forcing it past the last in the direction to increase the 80 spreading action of the pin when the horn engages a shoe upon the last.

5. A last holder for boot and shoe machines, comprising a bearing for the last and a pin engaging from below the walls 85 of the last hole, and constructed and adapted for increasing its holding action upon the last upon a movement of the last away from said bearing, and a pair of movable shoe horns adapted to be raised between the last 90 and the upper, the lifting movement of the horns being produced by means of a pedal, this motion of the horns aiding to increase the spreading action of the pin.

6. In a device of the character specified, 95 the combination with means for holding a last, of means for stripping the upper from the last and comprising a pair of shoe horns, mechanism for adjusting the horns toward and from the last position, and actuating 100 means for the horns.

7. In a device of the character specified, the combination with means for holding a last, of a pair of shoe horns for stripping an upper from the last, a pair of guide rails 105 for said horns, and means for shifting the horns upon said guide rails.

8. In a device of the character specified, the combination with means for holding a last, of a pair of shoe horns for stripping an 110 upper from the last, a pair of guide rails for said horns, means for adjusting said guide rails toward and from each other, and means for shifting the horns upon said guide rails.

9. In a device of the character specified, the combination with means for holding a last, of a pair of shoe horns for stripping an upper from the last, a pair of guide rails for said horns, means for adjusting said 120 guide rails toward and from each other comprising a nut associated with each guide rail and a turnbuckle associated with said nuts, and means for shifting the horns upon said guide rails.

10. In a device of the character specified,

the combination with a bearing for a last, of
a last pin associated with such bearing,
shoe horns for stripping an upper from a
last carried by said pin, actuating mecha-
nism for said pin and horns, a hollow up-
right housing for said actuating mechanism,
and a cover plate for said housing comprising
a base-plate for the last bearing and pin.

In witness whereof, I have hereunto
signed my name in the presence of two sub-
scribing witnesses.

GEORGE PARMENTIER.
